US00D945357S

(12) **United States Design Patent** (10) Patent No.: **US D945,357 S**
 Kang et al. (45) Date of Patent: ** Mar. 8, 2022

(54) **FOLDABLE SOLAR PANEL**

(71) Applicant: **XIAMEN TOPUNIVE TECHNOLOGY CO., LTD.**, Fujian (CN)

(72) Inventors: **Yao Kang**, Fujian (CN); **Huaqiang Mei**, Fujian (CN); **Yuanjin Chen**, Fujian (CN)

(73) Assignee: **XIAMEN TOPUNIVE TECHNOLOGY CO., LTD.**, Fujian (CN)

(**) Term: **15 Years**

(21) Appl. No.: **29/750,537**

(22) Filed: **Sep. 15, 2020**

(30) **Foreign Application Priority Data**

Jul. 10, 2020 (CN) 202030372579.0

(57)

CLAIM

The ornamental design for a foldable solar panel, as shown and described.

DESCRIPTION

FIG. 1 is a perspective view of a foldable solar panel showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, showing the status when folded.

1 Claim, 6 Drawing Sheets
